DESIGN FOR A JAR AND LID.

Design No. 20,293, dated November 11, 1890.

UNITED STATES PATENT OFFICE.

RICHARD WILLM. BINNS, OF WORCESTER, ENGLAND.

DESIGN FOR A JAR AND LID.

SPECIFICATION forming part of Design No. 20,298, dated November 11, 1890.

Application filed April 21, 1890. Serial No. 348,920. Term of patent 7 years.

To all whom it may concern:

Be it known that I, RICHARD WILLIAM BINNS, director of the Royal Porcelain Works, Worcester, and a subject of the Queen of Great Britain, residing at Worcester, in the county of Worcester, in the Kingdom of Great Britain, have invented and produced a new and original Design for a Jar and Lid, of which the following is a specification, reference being had to the accompanying photograph, forming a part thereof.

The leading features of the design are as follows: a conical base formed of a plain conical part surmounted with a filigree-work in relief above; a somewhat ovate body with broad very shallow flutings, and with small leaf ornaments in the channels of the flutes near top and bottom, and a lid surmounting the same having a base very similar but shallower to the base of the jar, surmounted by a gathered-in portion resembling closely a gathered-in crown, there being ornamental openings to carry out the design, and also a conical handle, a ring of coronal points, and a projecting

pinnacle, causing it to still further resemble a crown. The design is throughout circular in general horizontal contour.

What I claim is—

The design for a jar and lid, herein shown and described, the same comprising an ovate body with broad and shallow flutings, a conical base with filigree-work in relief on the upper part, a lid resembling a crown having a base very similar to the base of the jar, openings in the lid to resemble openings in a crown, and a conical handle having coronal points and pinnacle, still further carrying out the idea of a crown.

In testimony whereof I have signed my name to this specification in the presence of two subscribing witnesses.

RICH. WILLM. BINNS.
